UNITED STATES PATENT OFFICE.

WILLIAM R. KINNEAR, OF COLUMBUS, OHIO.

MACHINE FOR ROLLING SHEET METAL.

SPECIFICATION forming part of Letters Patent No. 515,402, dated February 27, 1894.

Application filed December 12, 1891. Serial No. 414,775. (No model.)

To all whom it may concern:

Be it known that I, WILLIAM R. KINNEAR, a citizen of the United States, residing at Columbus, in the county of Franklin and State 5 of Ohio, have invented new and useful Improvements in Sheet-Metal Rolls, of which the following is a specification.

My invention relates to machines for rolling sheet metal and particularly the kind 10 that have a series of pairs of reducing rolls in which a roll of each pair has an adjustable and yielding support.

It consists of the improved construction 15 and arrangement of parts herein described, substantially as shown in the accompanying drawings, and pointed out in the claims.

In the drawings: Figure 1, is a side elevation of the machine. Fig. 2, is a longitudinal section of the same. Fig. 3, is an enlarged detail showing the tension device and means for securing the same. Fig. 4, is an 20 illustrative diagram of a sheet of metal, the dotted lines showing the direction of the flow of the metal during the different stages of 25 the operation.

In the drawings, the letters A A designate the straightening rolls. These rolls are mounted in the frame X between the uprights X' on the sides of which are guides to 30 control the movement of the journal boxes A'. The movement or adjustment of the journal boxes is accomplished by the screws B on the ends of which the journal boxes rest. These screws B engage threads in the bottom side 35 rails and in the top side rails of the frame. The top side rails are composed of a number of contiguous sections or plates C, and each of these plates or sections has upturned ends over which fit caps D. The cap D is 40 secured in place by means of the screws E which are driven into threaded holes in the uprights X' and pass loosely between the adjoining plates C. It is by means of this mounting that I am permitted to introduce 45 a single tension device at the junction of the plates which in the drawings is shown as a layer of rubber F. This rubber I insert between the turned-up ends of the plates C and the caps D. By this rubber being interposed between the plates C, to which the

upper roll A is connected by means of the screw B and the caps D, which hold them down in place, any unexpected strain will be taken up and the machine not become jammed or broken. It will also be seen that in constructing one of the side rails of contiguous sections and placing a single tension device to act simultaneously on the adjacent ends of the section, besides effecting a large saving in the cost of apparatus, one of the main 55 advantages resides in the fact that two pairs of rolls may be adjusted or removed by the manipulation of a single adjusting device.

The mountings I have just described are in the sides of the frame and receive the ends 60 of the roll A, at which points I am permitted, by the construction, to obtain the greatest pressure on the sheets of metal, there being no chance to spring here as in the center. This arrangement places the stretching 65 points on the edges of the sheets and causes the excess of drawing to take place there, as is shown in Fig. 4, of the drawings, in which the dotted lines indicate the lines of draft. To obtain a hold on the sheets the alternating 70 rolls are raised and lowered, increasing the frictional hold. To stretch the metal the succeeding rolls are given a gradually increased speed from the end where the sheets are introduced. This I accomplish by any of 75 the well-known means. As shown in the drawings, the pairs of rolls are connected by the interposed gears G which are held in position by means of the bars or straps H, the bars being loosely connected to the shafts of the adjoining pairs of rolls. By this way of coupling the gears I am permitted to adjust the rolls independently, the interposed gears G being constantly maintained in their position 80 by the straps H.

Having thus described the invention, what I claim is—

1. In a metal rolling machine, the combination of a frame X, a series of pairs of reducing rolls in said frame, a rail of the aforesaid 95 frame made in contiguous sections C, each section supporting a journal box of one of the rolls of each pair, and a single tension device placed at the junction of the sections constructed to act simultaneously on the adja- 100

cent ends of said sections, substantially as described.

2. In a metal rolling machine, the combination of a frame X, a series of pairs of reducing rolls in said frame, a rail of the-aforesaid frame made in contiguous sections C, each section supporting a journal box of one of the rolls of each pair, and a single tension device comprising the cap D fitting over the meeting ends of the sections, cushion F between

the cap D and the adjacent ends of the sections, and screw E for securing the cap in place, substantially as shown and described.

In testimony whereof I have hereunto set my hand this 3d day of December, 1891.

WILLIAM R. KINNEAR.

Witnesses:

B. D. KINNEAR,
A. N. VAN DEMAN.
